MAGNET WIRE

Orville F. Freeland, North Muskegon, Mich., assignor to Anaconda Wire & Cable Company, New York, N. Y., a corporation of Delaware

Application December 7, 1937, Serial No. 178,516

5 Claims. (Cl. 174—124)

This invention relates to electric conductors of the smaller sizes and more particularly to conductors which are used in winding coils, solenoids or other electrical apparatus. The wire used in secondary windings of transformers and similar apparatus is necessarily of extremely small diameter, so that the completed coil will not be excessively expensive or bulky. It is possible to use conductors of small diameter since the current is almost infinitesimal, while the potential may be extremely high: at the present time magnet wire is commercially manufactured in sizes as small as #42 Awg. which has a nominal diameter of 0.0025". Such a wire has an ultimate strength of between two and three ounces.

While conductors of this order of fineness are not required to carry tensile stress while in service, a certain amount of tension is unavoidable during the manufacturing processes. Since a secondary for a moderate sized transformer may contain many thousand turns of wire, the windings must be applied at high speed if production is to be economical. Furthermore, the windings must be firm and hold their position within the coil as mechanical abrasion may destroy the insulation if the wire is loose and free to shift. Because of the high speed and the tension necessary to produce a satisfactory assembly, the finer sizes of conductor may be over-stressed and broken during winding. If this occurs the coil must either be rejected or tediously repaired by brazing the broken wire and re-insulating it. The loss caused by delays of this nature is especially high when many coils are wound in a single machine at the same time, since production on all coils must be stopped.

Having the foregoing in mind the present invention relates to a magnet wire which is reinforced with a high-strength non-conducting strand. Other features of the invention will be described in connection with the accompanying drawing in which:

Figure 1 is a perspective view, greatly enlarged, of a small section of magnet wire constructed in accordance with the present invention, the covering sheath being progressively removed.

Figure 2 is a cross-section taken in plane AA of Figure 1, illustrating the relation of the conductor and reinforcing strand in the completed wire.

Figure 3 is a view similar to Figure 1 of a section of magnet wire insulated with a plastic coating.

Referring to Figure 1, the metallic wire 11,

preferably formed of copper, may be coated in accordance with present practice with a layer of enamel 13 which possesses high-dielectric strength and resistance to abrasion and bending. For purposes of explanation this conductor may be considered to be of a size commonly used in secondary windings, for example #37 Awg. The diameter of this wire is 0.0045" and its area is 20 circular mils or 0.0000157 square inch. Assuming that the strength of the copper is 36,000 pounds per square inch, which is the maximum value for soft wire, the ultimate strength of the wire would be 0.57 pound. A conductor of such low strength may of course be easily broken between the fingers and must be handled with extreme care in manufacture. To reinforce the copper I have found that a strand of glass thread 15, composed of a multiplicity of twisted filaments may be laid parallel to the conductor 11 and secured in place by whatever outer jacket is furnished for the wire.

Glass yarns and threads are available at the present time which develop a strength approximately five times that of soft copper and the inclusion of a thread of this nature, whose diameter may be considerably less than that of the conductor, will supplement the strength of the copper to such a degree that the completed wire will withstand approximately four times the stress which may be carried by the metal alone. Furthermore the cross-sectional shape of the supplementary thread is readily deformed so that it assumes a crescent shape when bound to the conductor by an outer jacket; because of this, the external diameter of the wire is increased but slightly and a negligible amount of void area is introduced beneath the outer coating. As compared to a #37 Awg. wire which is not reinforced, my improved conductor has a cross-sectional area which is only fifty (50%) percent greater while the strength has been increased three hundred (300%) percent. The electrical characteristics of the wire of course remain unchanged.

A feature of this construction which is of special importance from the standpoint of corrosion lies in the fact that the reinforcing filament is non-metallic in nature and therefore there is no tendency to accelerate failure as would be the case if a dissimilar metal was employed. The outer jacket of the wire is comparatively unimportant, as far as this invention is concerned, since it serves merely to hold the reinforcing strands in position adjacent the conductor. As indicated in Figure 1, a serving 17 of silk or cotton threads may be used or as indicated for this

purpose. In Figure 3, a layer 19 of enamel, lacquer or resin, applied either from a solution or extruded about the wire, will be equally satisfactory.

5 While I prefer to use glass threads as a reinforcing medium, since this material possesses high-strength and resistance to heat and absorption of moisture, there may be situations where a fibrous strand of other composition would be 10 satisfactory for this purpose.

What I claim is:

1. An electric conductor comprising a metallic wire and a non-metallic reinforcing strand laid parallel to said metallic wire, the tensile strength 15 of said reinforcing strand being at least equal to that of said metallic wire, said reinforcing strand being located adjacent the outer surface of said metallic wire and bound to said wire by an outer non-metallic jacket.
- 20 2. An electric conductor comprising a metallic wire and a non-metallic reinforcing strand laid parallel to said metallic wire, said reinforcing strand being located wholly externally of said metallic wire, the strength of said reinforcing strand being at least equal to that of said metallic wire.

3. An electric conductor comprising a metallic wire and a reinforcing strand composed of glass filaments laid parallel to said metallic wire, said reinforcing strand only partially enclosing said wire and bound to said wire by an external fibrous jacket. 5

4. An electric conductor comprising a metallic wire and a reinforcing strand composed of glass filaments laid parallel to said metallic wire, the tensile strength of said reinforcing strand being 10 at least equal to that of said metallic wire, said reinforcing strand being bound to said metallic wire by an outer jacket and deformed to partially conform to the surface of said metallic wire. 10

5. An electric conductor comprising a metallic wire and a reinforcing strand of glass filaments laid parallel to said metallic wire, said reinforcing strand being located wholly externally of said metallic wire and having a tensile strength at least equal to that of the metallic wire, said reinforcing strand and said metallic wire being bound into a 15 unitary structure by an outer jacket which deforms said reinforcing strand to partially conform to the surface of said metallic wire. 20
